UNITED STATES PATENT OFFICE.

HENRY E. SKEELS, OF ROCHESTER, NEW YORK.

EXTENSION LADDER.

Application filed November 26, 1926. Serial No. 150,695.

The present invention relates to extension ladders and an object thereof is to provide an extension ladder having an adjustable section held in its shifted position by a latch which is controlled in a novel manner by a cable through which the section is adjusted. Another object of the invention is to provide an extension ladder in which an adjustable section has means adjacent its upper-end for cooperating with the latch which holds the adjustable section in its adjusted position so that the latch will not interfere with the separation of the sections. Still another object of the invention is to provide novel means for strengthening the upper end of a latch carrying section of the ladder so that a latch may cooperate with the rung of the latch carrying section without any danger of the rung breaking due to its being weakened by being mortised in the uprights of the latch carrying section.

To these and other ends, the invention consists of certain parts and combinations of parts, all of which will be hereinafter described; the novel features being pointed out in the appended claims.

In the drawings:

Fig. 1 is a plan view of a ladder constructed in accordance with this invention. Fig. 2 is a fragmentary plan view showing one section of the ladder locked in an adjusted position upon another section.

Fig. 3 is a similar view showing the latch shifted to permit the relative adjustment between the two sections.

Fig. 4 is a section on the line 4—4, Fig. 2.

Fig. 5 is a section on the line 5—5, Fig. 3.

Fig. 6 is a vertical fragmentary section showing the manner in which the latch cooperates with a guide portion of an adjacent section to permit the separation of the sections.

Fig. 7 is a fragmentary detail view showing the manner in which the two sections may be interlocked for the purpose of producing a stepladder.

Fig. 8 is a detail view of the hook at the end of the flexible operating connection.

In the drawings a ladder of only two sections is illustrated but it is apparent that any number of sections may be assembled in the same manner. In fact the upper section in the present instance is provided with means which will permit a third section to be adjusted thereon.

The lower section in the illustrated em-

bodiment comprises two uprights 1 connected by rungs 2. Arranged to operate on this lower section is an upper section having uprights 3 connected by rungs 4. The width of the upper section is slightly less than the width of the narrowest portion of the lower section so that the upper section may fit between the uprights of the lower section and slide on the rungs of such lower section.

To the end that the sections may be held together, each section is provided at its upper end with guide hooks 5 preferably in pairs secured to the opposite faces of the uprights of each section, projecting rearwardly from the uprights and turned inwardly so to engage about another section. These guide hooks are arranged in pairs in spaced relation near the upper end of a section so that the next lower section may be moved upwardly only a short distance on the section sliding thereon in order to disconnect such lower section from the section sliding on it.

In order to shift one section on another an adjusting means is provided between each two sections. The adjusting means in this instance comprises a rope or flexible operating connection 6 preferably detachably secured by a hook 7 to an eye 8 secured in this instance to the lowermost rung of the section to be adjusted. From its secured point, the flexible connection or rope is extended upwardly and passes about a pulley 9 arranged in this instance on the uppermost rung of the section on which the shiftable section is adjusted and from the pulley 9 the rope or flexible connection extends downwardly toward the bottom of the ladder where it may be operated by hand to effect the elevation or the lowering of the section to be adjusted.

With the end in view of sustaining a shiftable section in different adjusted positions on the next lower section, a latch 10 is provided in this instance formed from a metal rod bent to provide two end projections 11 serving as pintles and journaled on the section which remains stationary during the adjustment of a section thereon. This latch is a substantially V shaped member and the pintles 11 are disposed near the outer face of the section slightly above the plane of the upper surface of one of the upper rungs of the section preferably the 110 rung next to the highest rung on the section, so that the side of the latch may cooperate

with the upper surface of such rung and in this way add strength to the latch while the rung acts as an abutment. The latch projects beyond the rear face of such rung and 5 into the path of the rung of the section adjustable on the section carrying the latch. In this way when the adjustable section moves upwardly, the rungs of such adjustable section cooperate with the under side of 10 the latch and shifts such latch out of the part of the rungs, the latch returning to latching position by gravity so as to sustain the adjustable section in its adjusted position by engaging beneath the latch rung that 15 shifts said latch during such elevation.

With the end in view of controlling the latch so as to effect the lowering of adjustable section, the latch has a recess or notch 20 bent or formed in the outer edge thereof, and during the shifting of the adjustable section both strands of the flexible connection 6 operate in this notch. The lowering of the upper section is effected by shifting the downwardly extending strand of the 25 flexible connection laterally while holding the flexible connection under tension as will be seen by referring to Figs. 3 and 5. The flexible connection rides on an inclined wall of the recess 12 and engages the free edge 30 of the latch 10 holding the latter elevated against the stop 13 and out of the path of the rungs on the adjustable section, permitting the adjustable section to be lowered gradually through the flexible connection 6 35 until the two sections are completely lowered to the position illustrated in Fig. 6.

It will be noted that when the adjustable section is lowered to the position shown in Fig. 6 the latch 10 is held away from latching position. This result is obtained by providing on each section, guide pieces 14, these 40 guide pieces being arranged in pairs on the inner face of the uprights of each section. The ends of the guides are bevelled at 15 to permit the latch to slide freely off and on the guides. The guides are positioned adjacent the upper end of each section so that as 45 any one section moves to the horizontal plane of another, the guides on such section cooperate with the sides of the latch 10 and hold it in unlatching position as shown in Fig. 6. These guide pieces 14 preferably extend between the uppermost rung of a section to 50 a point below the underside of the next highest rung. In this way they perform the additional function of strengthening that rung of the ladder section with which the latch 10 cooperates, the guide pieces being mortised to receive such rungs and being at the 55 same time fastened to the inner faces of the two uprights on both sides of said rungs. Owing to the fact that, when two ladder sections lie in the same plane, the latch on the lower will engage the guide pieces of the 60 upper section, it is possible to discon-

nect the sections without interference by the latch. All that is necessary is that the lower of two sections be elevated on the other section and the latch on the lower section will travel up the guide pieces 14 and off 70 the end of the next higher section. The lower pair of guide hooks 5 are situated only a short distance beneath the latch of a section so that shortly after the latch of a lower section passes off the end of the next 75 higher section, the lowermost guide pieces 5 of the lower section will be disengaged from the uprights of the upper section and the two sections will be separated. The rope or flexible connection 6 may through the 80 detachable hook 7 be disconnected with the next higher section before or after the separation.

The uppermost guidehooks 5 on two sections lend themselves to the making of a 85 stepladder from the two sections. This result is secured as shown in Figure 7 by passing the upper end of the uprights 3 between the inturned ends of the guide hooks 5 and the upper rung 2 of the lower section as in Fig. 7, the upper end of the upper sections being notched at 16 so that they may 90 rest upon the rung 2 and interlock therewith. When in this position the lower edge of the upper rung rests upon the upper edges of 95 the hooks 5 projecting from the uprights 3 so that an effective interlocking of the upper ends of the two ladder sections is obtained.

From the foregoing it will be seen that there has been provided an extension ladder in which the latch which sustains an adjustable section is so constructed that it may be readily controlled by the operating rope or flexible connection through which the extension of the ladder is obtained. A novel 105 means is provided for strengthening the upper end of each section so that a rung may be employed as a stop or abutment for a latch while such latch is supporting an adjustable section. Means is also employed at 110 the upper end of an adjustable section for cooperating with the latch on the adjacent lower section in order to maintain the latch out of latching position when two sections 115 are moved to the same plane so that the lower section may be lifted from the upper section without any interference by the latch.

What I claim as my invention and desire to secure by Letters Patent is:

1. An extension ladder comprising two sections, one of which is adjustable on the other, a latch carried by the lower section near the upper end of the latter to cooperate with the rungs of the upper section, a flexible connection secured to the upper section near the lower end of the latter, extending upwardly and having sliding engagement with the lower section above the latch and extending downwardly and cooperating with the latch to control the movement of the 120 125 130 135 140 145 150 155 160 165 170 175 180 185 190 195 198

upper section, and means carried by the upper end of the upper section for cooperating with said latch as the upper section moves to lowered position on the lower section in order to hold said latch out of latching position with the uppermost rung of the upper section when released by the flexible connection so that the lower section may be disconnected from the upper section by lifting the lower section upwardly on the upper section.

2. An extension ladder comprising a section having guide pieces extending downwardly from its upper rung to points below the next lower rung, said guide pieces being mortised to receive said next lower rung and being secured to the inner faces of the uprights of such section on opposite sides of the mortises, a latch pivoted to said section above the rung next below the highest and adapted to cooperate with the upper face of said rung in order to engage beneath the rungs of another section.

3. An extension ladder comprising two ladder sections, each having rungs, a latch pivoted to the lower one of said sections to

engage beneath the rungs of the other and formed with a recessed portion between the pivotal axis and the free or swinging edge of the latch, said recessed portion having one wall thereof forming a surface at an oblique angle with reference to the pivotal axis of the latch and extending to the swinging edge of the latch, a guide pulley mounted at the upper part of the lower section to turn about an axis extending transversely of the plane of the ladder section, and a flexible controlling member secured to the lower portion of the adjustable section, extending upwardly from said secured portion through the recess in the latch to and about the guide pulley and having a portion extending downwardly to lie in the recess of the latch and to move laterally in the direction of the pivotal axis of the latch in order to cooperate with the inclined wall of the recess to move said latch on its pivot and then shift into engagement with the swinging edge of the latch in order to hold said latch out of latching position.

HENRY E. SKEELS.
